CLAIM

The ornamental design for a vegetable chopper, as shown and described.

DESCRIPTION

FIG. 1 is a perspective view of a vegetable chopper showing my new design.

FIG. 2 is another perspective view of a vegetable chopper;
FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded perspective view of the vegetable chopper.

The broken lines shown in the figures depict portions of the vegetable chopper that form no part of the claimed design.
